AMMUNITION CHARGING DEVICE FOR
AUTOMATIC ARMSBernard Maillard, Geneva, Switzerland, assignor
to Brevets Aero-Mecaniques S. A., a corpora-
tion of SwitzerlandApplication May 25, 1945, Serial No. 595,790
In Switzerland June 22, 1944

3 Claims. (Cl. 89—33)

1

The present invention relates to cartridge cases for firearms.

The object of my invention is to provide a cartridge case which is of simple construction and reliable in operation.

A preferred embodiment of the present invention will be hereinafter described with reference to the accompanying drawings, given merely by way of example and in which:

Fig. 1 is a vertical section on the line 1—1 of Fig. 3 of a cartridge case according to my invention;

Fig. 2 is a section of this case on the line 2—2 of Fig. 3;

Fig. 3 is a horizontal section on the line 3—3 of Fig. 1.

The cartridge case shown by the drawings includes a vertical elongated magazine 10, with a sliding member 11 movable vertically therein in piston-like fashion. Magazine 10 is adapted to accommodate four columns of cartridges 15 bearing freely upon one another and having their axes horizontal and parallel to two of the vertical walls of the magazine. These columns of cartridges are supported by sliding member 11.

Said member 11 is urged upwardly by a cable 12 connected to member 11 through a spring 13.

At the top, the side walls of magazine 10 that are parallel to the axes of the cartridges converge toward each other as shown at 25 so as to form finally a narrow conduit 26 through which only one column of cartridges can pass. The outlet of this conduit 26 opens into the firearm feed passage 16.

In order to guide the cartridges arriving in four vertical columns, I provide a deflector 17, of quadrilateral prismatic shape provided in the middle top portion of the magazine and adapted to cooperate with the converging walls 25 of magazine 10, so as to cause first the two columns of cartridges on either side of deflector 17 to merge into a single one, and then the two columns thus formed to merge in turn into a single one which moves through conduit 26.

Deflector 17 is hollow and, on the inside thereof, there is provided a pulley 18 about which passes cable 12 which, after passing about another pulley 19, is finally connected to a motor 14 which, through said cable 12, urges support 11 in the upward direction.

In a general manner, while I have, in the above description, disclosed what I deem to be practical and efficient embodiments of my invention, it should be well understood that I do not wish to be limited thereto as there might be changes

2

made in the arrangement, disposition and form of the parts without departing from the principle of the present invention as comprehended within in the scope of the accompanying claims.

5 I claim:

1. Apparatus for feeding to an automatic firearm cartridges having no connection between them comprising an elongated magazine for receiving a plurality of columns of cartridges positioned therein with their axes transversely of the magazine, means slidably mounted in said magazine for movement longitudinally thereof and engaging the end cartridges of the columns for moving said columns of cartridges through the magazine, hollow cartridge deflecting means positioned intermediate the columns of cartridges and at the discharge end of the magazine, a flexible traction member connected to said moving means for drawing the same through the magazine, guide means within said hollow deflecting means for guiding said flexible traction member and a motor independent of the magazine for actuating said flexible traction member.

2. Apparatus for feeding to an automatic

25 firearm cartridges having no connection between them comprising an elongated magazine for receiving a plurality of columns of cartridges positioned therein with their axes transversely of the magazine, said magazine having a width slightly less than the sum of the diameters of four cartridges so that the cartridges of four columns of cartridges will be in over-lapped relation, means slidably mounted in said magazine for movement longitudinally thereof and engaging the end cartridges of the columns for moving said columns of cartridges through the magazine, a flexible band traction member connected to said moving means for drawing the same through the magazine and extending between the inner pair of four columns of cartridges in said magazine, hollow cartridge deflecting means positioned intermediate the columns of cartridges and at the discharge end of the magazine, guide means within said hollow

35 deflecting means for guiding said flexible traction member and a motor independent of the magazine for actuating said flexible traction member.

3. Apparatus for feeding an automatic firearm

50 with cartridges having no connection between them which comprises, in combination, an elongated magazine for receiving a plurality of columns of cartridges positioned therein with their axes parallel between them and transverse to the longitudinal direction of said magazine, an

45 deflecting means for guiding said flexible traction member and a motor independent of the magazine for actuating said flexible traction member.

output guiding channel adapted to receive a single column of cartridges from the discharge end of said magazine, a hollow cartridge deflector located in the middle portion of said discharge end of the magazine opposite the inlet of said output channel, means slidably mounted in said magazine for movement longitudinally thereof adapted to engage the end cartridges of the columns to push them longitudinally toward said discharge end, at least one flexible traction member connected to said slidable means extending longitudinally of said magazine, a pulley for said flexible traction member located inside said deflector, and motor means on the outside of said magazine for exerting a continuous pull on said traction member passing on said pulley.
